COMBINED DISPENSING CAP AND HEATER FOR A PRESSURIZED CONTAINER

George L. Schick, Trumbull, Conn., assignor to Warner-Lambert Company, Morris Plains, N.J.

Filed July 20, 1973, Ser. No. 381,187

Term of patent 14 years

Int. Cl. D9—07

U.S. Cl. D9—258

FIG. 1

FIG. 2

FIG. 3

FIG. 4

FIG. 1 is a left side elevational view of a combined dispensing cap and heater for a pressurized container showing my new design;

FIG. 2 is a front elevational view thereof;

FIG. 3 is a top plan view thereof; and

FIG. 4 is a bottom plan view thereof.

I claim:

The ornamental design for a combined dispensing cap and heater for a pressurized container, as shown.
